VEGETABLE GRATER

William Marcus, Cleveland, Ohio

Application January 26, 1950, Serial No. 7,505

Term of patent 7 years

(Cl. D89—1)

To all whom it may concern:

Be it known that I, William Marcus, a citizen of the United States, residing at 2528 Mayfield Road, Cleveland, Cuyahoga County, Ohio, have invented a new, original, and ornamental Design for a Vegetable Grater, of which the following is a specification, reference being had to the accompanying drawing, forming a part hereof.

Fig. 1 is a perspective view showing the top, one side, and one end of a vegetable grater embodying my new design;

Fig. 2 is a perspective view showing the bottom, the other end and the other side of the device of Fig. 1; while

Fig. 3 is a perspective view showing the underside of the cover of Fig. 1.

The dominant features of my design are shown in full lines and the grater blade element is shown in broken lines for illustrative purposes only.

I claim:

The ornamental design for a vegetable grater, as shown and described.

WILLIAM MARCUS.
